UNITED STATES PATENT OFFICE.

LAWRENCE A. WAGNER, OF YOUNGSTOWN, OHIO.

REINFORCED PLASTIC FENCE-POST WITH BASE.

1,271,105.

Specification of Letters Patent. Patented July 2, 1918.

Application filed August 14, 1916. Serial No. 114,669.

To all whom it may concern:

Be it known that I, LAWRENCE A. WAGNER, a citizen of the United States, residing at Youngstown, in the county of Mahoning and State of Ohio, have invented 5 certain new and useful Improvements in Reinforced Plastic Fence-Posts with Bases, of which the following is a specification.

The present invention relates to improvements in reinforced plastic fence posts with 10 bases, and more particularly to a post of a type described in my prior United States Patent No. 1,162,322 of 1915. In the post referred to I have described and claimed a fence post formed of plastic material and 15 provided upon one face with a longitudinally extending groove, formed V-shaped in cross section and having transverse openings which lead into the groove, metallic sleeves arranged within the transverse openings together with a tying element to secure the wires to the post.

The present invention has for its object 20 to modify and improve the reinforced plastic fence post with base, for the purposes hereinafter more fully described.

Another object of the invention is to provide a post of the above mentioned character, which is simple in construction, inexpensive to manufacture, durable, easily 25 transported, strong and convenient in use.

Another object of this invention is to provide a bonding rod as a part of the anchor base in conjunction with the metallic reinforcing members, being U-shaped at the 30 lower extremity and passing directly underneath the bonding rod and ends extending upward disposed near the corners of and within the plastic material of the post.

Another object of the invention is to provide a reinforced brace portion, when wanted, positioned at the upper end of the post, consisting of a recess adapted to receive a brace for the post, the said reinforcing being made doubly strong by the bending down of one end of the pair of reinforcing members crossing the opposite end of the reinforcing members immediately above said recess.

With these and other objects in view, the invention consists in certain novel features of construction as hereinafter shown and described, and then specifically pointed out in the claim and in the drawings illustrative of the preferred embodiment of the invention.

Figure 1 is a perspective view of the fence post embodying my invention.

Fig. 2 is a longitudinal sectional view 60 through the same.

Fig. 3 is a detail horizontal sectional view.

Fig. 4 is a detail view showing the metallic reinforcing members in conjunction with a bonding rod which is a part of the anchor 65 base.

Corresponding and like parts are referred to in the following description and indicated in all the views and drawings by the same reference characters.

The improved post 1 is formed of concrete of any suitable composition or compound and comprises a base portion with a transverse opening to receive a bonding rod 3. See Figs. 1 and 2.

The post 1 is provided upon one side or face with a longitudinal groove 6 which is preferably V-shaped in the horizontal cross-section, as more clearly shown in Fig.

1. The post 1 is provided with spaced 80 transverse openings 7, which lead into the groove 6 as more clearly illustrated in Figs. 1 and 2. Disposed within the transverse openings 7 are preferably metallic attaching members 4, more specifically described 85 and claimed in my patent above mentioned. These attaching members 4 secure the wires 5 to the fence. See Fig. 1. It will be noticed by referring to Fig. 1, that the bonding rod 3 of the base portion passes through 90 the lower portion of the post 1 at right angles to the wires 5 thereby providing greater resisting power should pressure be applied against either side of the fence constructed with my improved post.

The post 1 is reinforced by metallic reinforcing members 2, these reinforcing members passing directly underneath the bonding rod 3 and extending upwardly near each corner of the plastic post 1 as shown in Figs. 100 3 and 2 thereby securely binding the anchor base to the post.

The post 1 may be provided upon one of the adjacent surfaces or faces to the face provided with the V-shaped groove, with a 105 recess 15, formed in the plastic portion of the post to receive a bracing member when required. The reinforcing members 2 having one arm of the extended portion longer than the other when being shaped for reinforcing purposes are bent at point 10 of the upper portion thereby forming an acute

- angle, the downturn portion 12 crossing the other end of the reinforcing member 2 at point 13, thereby leaving a projecting end 11 above the downturn portion 12.
- 5 In referring to Fig. 2 it will readily be seen that the upper portion of the post provided with the reinforcing members bent and crossing to the opposite side of the post is durably and additionally reinforced and reduces the danger of the post breaking in any portion of it and especially reduces the danger of the upper portion of the post 16 from being dislodged from the post 1 when the brace is required.
- 15 It will further be seen by referring to Figs. 4 and 2 that by the passing of the reinforcing members 2 underneath the bonding rod 3, the reinforcing members 2 come in contact with the bonding rod 3 at the lower portion 14 of said reinforcing members 2, thereby joining the entire reinforcing structure so that the post will stand extreme strains or pressure which may be exerted from any surface of the post. It
- 20 will also be seen by referring to Fig. 2 that the bending of the reinforcing members 2 at angle 10 that the reinforcing members 2 are securely held from slipping due to pressure or strain at contact point 14 of reinforcing members 2 by bonding rod 3 when pressure or strain may be present.
- 25 It will also be seen by referring to Fig. 2 that the downturn portion 12 of reinforcing members 2 insures the post from checking or spreading apart, if by any means it should become cracked, for the acute angle formed at point 10 will not allow the reinforcing members 2 to slip in their embedding or body portion of post 1.
- 30 40 It will also be seen by referring to Figs. 2 and 3 that members 2 and 3 situated and bonded together as they are in the post insures the post from breaking from the anchor or breaking in any other portion of the post and also prevents the post from heaving or raising from its place in the earth and also insures the post remaining perpendicular in the position it is placed in the earth.
- 45 50 In the construction of this post a transverse opening is provided by means of the bonding rod 3 and the mold formed to shape the post having within it the reinforcing members 2 and 3 as arranged and shown in Fig. 4. The bonding rod 3 is to be withdrawn after the post 1 has been molded 55 allowing sufficient time for the mixture to set. This will facilitate the transportation of the post. When the post is to be placed the ground is excavated to a desired depth, 60 the bonding rod 3 is driven into the transverse opening at the lower portion of the post, the post is then placed in the desired position and concrete or plastic material 8 is poured around the post and completely embedding the extended ends of the bonding rod 3 thereby securely bonding the base to the post and forming a complete anchor. The soil 9 is then filled in above the concrete anchor 8 thus formed to the level of the 65 ground or the desired height.
- It is to be understood that the form of my invention herewith shown and described is to be taken as a preferred example of the same, and that various changes in the shape, size, and arrangement of the same may be resorted to without departing from the spirit of the invention or the scope of the subjoined claim.
- What I claim is:—
- In a fence post of the class described, the combination of a body portion of a post formed of plastic material, metallic reinforcing members extending longitudinally of and embedded within the post, said reinforcing members spaced apart and passing directly underneath a bonding rod extending through the post at right angles to the fence wires attached to the post, said reinforcing members extending longitudinally near the corners of the post, with downturned ends of said reinforcing members crossing and projecting beyond opposite ends of reinforcing members, a recess formed immediately below the projection formed by the crossing of the ends of reinforcing members above described.
- In testimony whereof I affix my signature in the presence of two witnesses.
- LAWRENCE A. WAGNER.
